UNITED STATES PATENT OFFICE.

CLAUDE E. BOWERS, OF LOS ANGELES, CALIFORNIA.

STUCCO NAIL.

Application filed March 13, 1926. Serial No. 94,385.

This invention relates to a novel form of nail designed to be used for securing and holding in position wire netting to a building wall surface.

5 A main object of my invention is to provide a "stucco" nail formed of a single piece of metal bent into such form that when applied to a building wall surface it will hold the plaster receiving wire netting securely thereto and in parallel spaced relation to the wall surface.

Another object is to provide a nail that will automatically stretch the plaster receiving netting secured thereto when the nail is driven into the wall surface, and which is provided with means for securing the netting against accidental displacement prior to the placement of the plaster coats.

Further objects and advantages will be 20 come apparent from the following specification reference being had to the accompanying drawings, in which;

Fig. 1 is a partial elevation of a frame building wall, parts being broken away to 25 disclose the construction.

Fig. 2 is a side elevation of a nail showing the first step of securing the same to a wall.

Fig. 3 is a similar view showing the second step of securing the wire netting thereto.

Fig. 4 is a similar view with the nail forced into position, and in dotted lines its initial position as shown in Fig. 2, illustrating the manner of automatically stretching the wire netting secured thereto.

Fig. 5 is another view showing the nail driven into position and the hook member bent over to hold the netting with a plaster coat applied.

Fig. 6 is an enlarged face view of a portion of a wall showing a nail driven into position and the netting secured thereto.

Referring more particularly to the drawings it will be seen that the nail 5 is formed of a single piece of wire of sufficiently heavy gauge to insure a perfect nailing operation. The wall penetrating portion 6 is pointed to enable the same to be readily driven into place, and at the upper end of said portion 50 the wire is bent downwardly at an angle to the penetrating portion to form a part 7 substantially equal in length to portion 6, the apex 8 of the angle thus formed by the said portions being utilized for driving the penetrating portion 6 into the wall. At the outer end 9 of part 7 the wire is bent to form

a short right angled portion 10. The outer end of this portion is again bent at right angles to form a part 11 of a length substantially equal to the length of part 10, the outer end 9 of portion 7, and the end 12 of portion 11 engaging the wall surface 13 when the nail is placed in driving relation thereto. The wire at the end of part 11 is again bent inwardly towards portion 11 in the form of an acute angle to provide a hooked portion 14 for receiving the wire netting 15 therein, as shown in the various views of the drawings.

The above described nail is designed for 70 securing plaster receiving wire netting in spaced relation to the walls of frame building constructions, such walls 16 usually consisting of a base plate 17, studding 18, having a coated building paper 20 secured thereto. In securing the wire netting 15 in parallel spaced relation to the wall surface the workman first drives into position a vertically disposed row of nails. A length of wire netting, such as the well known 80 "chicken" wire is then secured to the hooked ends of said row of nails at the juncture 21 of two strands of wire 22, 23, see Fig. 6 the hook ends 14 being bent over the wires as in Fig. 5 to secure the same from accidental detachment. Another vertical row of 85 nails are then driven a distance from the first row about equal to the width of the netting 15, the hook of each nail before it is driven being hooked to a portion of the wire 90 in the manner heretofore described. As the penetrating portion 6 is driven into the sheathing the portion 7 will be bent into substantially right angles thereto and disposed parallel to the sheathing surface, see 95 Fig. 4. During the bending of portion 7, the part 10 will be drawn upwardly into the position shown in full lines in Fig. 4, the hooked ends 14 drawing the wire netting forwardly towards the nail penetrating portion 100 and tightly stretching the same. This movement of part 10 not only stretches the netting which is important, but serves to bring the netting into uniform spaced relation to the wall surface, so that the plaster coat 24 105 will completely embed the wire therein, as shown in Fig. 5.

What I claim is:

1. As a new article of manufacture a single piece of wire bent to form a wall engaging portion provided with a penetrating point and another portion disposed at an

- angle thereto, the length of said last named portion being substantially the same length as the wall engaging portion, whereby the end of said last named portion will rest against the wall surface when the wall engaging portion is driven into a wall, and a third portion bent at an angle to said second named portion, the outer end of said portion being bent into hooked form.
10. 2. A stucco nail consisting of a single piece of wire provided with a wall penetrating point and bent upon itself to form an angular portion, the pointed leg of the angle when driven into the wall bending the other leg of the angle into a plane parallel with the wall surface, that portion of the wire extending beyond the angular portion being bent to form a hooked wire receiving end.
15. 3. A stucco nail consisting of a single piece of wire bent upon itself to form an acute angle, one leg of said angle forming a wall engaging portion and being pointed, that portion of the wire beyond the acute angular

portion being bent at an angle thereto its end being hooked to receive a wire, whereby 25 when the wall engaging portion is driven into the wall the other leg of the angle will be bent to cause the hooked end to lie substantially parallel to and beyond the wall surface.

30. 4. A stucco nail comprising a single length of wire bent intermediate its ends to form an angle less than a right angle, one of the legs of said angle being pointed for wall penetration, and a wire engaging portion having a hooked end extending at an angle to the other leg of the angle, whereby 35 when the penetrating leg of the angle is driven into a wall the wire engaging portion will be brought into substantially right 40 angled relation to the wall surface.

In witness that I claim the foregoing I have hereunto subscribed my name this 10th day of February, 1926.

CLAUDE E. BOWERS.
